BRICK WALL CONSTRUCTION

Herbert Alfred Faber, Cincinnati, Ohio

Application May 22, 1937, Serial No. 144,168

2 Claims. (Cl. 72—102)

This invention relates to brick walls, and particularly to hollow brick walls formed from component single walls united by stud formations.

Among the objects of the invention are to provide in brick wall constructions:

1. Concealed voids for the purpose of insulation.
2. A minimum of contact areas between component single walls defining the voids, without sacrifice of intimate interlocking of the single walls.
3. A novel type of brick, and a scheme for placing such brick in combination with ordinary types of brick for attaining thorough inter-tying of all the bricks in the respective component single walls.
4. Symmetry of structure.
5. Great structural strength and the ability to bear loads substantially uniformly throughout.

An outstanding structural feature of the invention is the provision of composite studs between the component single walls, integral alternately with one and the other of the single walls along their vertical extent. Both the component single walls and the composite studs are built up of brick, the bricks of the studs forming, in part, a portion of one or the other of the single walls.

In preferred embodiments, special L-shaped bricks are utilized in combination with the ordinary type of building brick. The projecting legs of certain groups of the L-shaped bricks are vertically aligned to form stud sections, and the stud sections projecting from one component single wall overlap the stud sections projecting from the other component single wall, alternately, from bottom to top of the wall, in forming the above mentioned composite studs.

In the drawing which illustrates but one embodiment of this invention:

Fig. 1 represents a front elevation of a fragment of a wall embodying the features of the invention. A portion of the front component single wall is broken out revealing the composite studs.

Fig. 2 represents a horizontal section taken on the line 2—2 of Fig. 1.

Fig. 3 represents a horizontal section taken on the line 3—3 of Fig. 1.

Fig. 4 represents a horizontal section taken on the line 4—4 of Fig. 1.

Fig. 5 represents a vertical section taken on the line 5—5 of Fig. 1.

Fig. 6 illustrates in perspective overlapping

L-shaped bricks in the wall construction of Fig. 1.

Referring to the drawing: The wall illustrated is hollow and comprises the component single walls 10 and 11, one parallel to, and substantially coextensive with the other. Each of the single walls 10 and 11 is built up from a plurality of bricks laid end-to-end horizontally forming courses and one upon another providing the vertical dimension of the wall.

Bricks of the usual building type are preferably employed. These may be molded from clay or a cementitious mixture. The standard American brick is rectangular in configuration with average dimension of $2\frac{1}{2} \times 4 \times 8$ inches. Such 15 bricks are indicated at 12 in the drawing.

In the illustrated embodiment, for providing the composite studs between the spaced component single walls, L-shaped bricks 13 are placed at appropriately spaced locations in each course of each single wall. The L-shaped bricks 13 are wholly integral and have a vertex portion 13a and a body leg 13b which, taken together, are coextensive in configuration and dimension with the usual bricks 12. The vertex portion 13a and the body leg 13b are advantageously identical in configuration and dimension. In addition, a leg 13c projects preferably at right angles to the body leg 13b. The length of projecting leg 13c is determined by the required thickness and other structural characteristics of the entire wall construction.

In constructing the wall, the component single walls are built up opposite each other, spaced apart, and usually mutually parallel. The bricks 12 are laid end-to-end with mortar in the customary manner. Interposed between groups of serially related bricks 12—in the illustrated embodiment there are three bricks 12 to each group—are L-shaped bricks 13 placed with their projecting legs 13c extending into the space between the single walls.

The L-shaped bricks 13 are so incorporated in each course at spaced locations along its horizontal extent that for a given group of consecutive courses in either of the component single walls 10 and 11, the projecting legs 13c of superimposed L-shaped bricks are vertically aligned. The so formed sets of vertically aligned projecting legs 13c extend into the space between the single walls and provide stud-sections for the wall.

In the present case, groups 14 of five consecutive courses of single wall 10 provide stud sections 14a at spaced locations along the horizon-

- tal extent of the wall. Likewise groups 15 of five consecutive courses of single wall 11 provide stud sections 15a at spaced locations along the horizontal extent of the wall.
- 5 Further, the L-shaped bricks 13 are preferably so placed in their respective courses that a stud section 14a of single wall 10 extends centrally between two adjacent stud sections 15a of the directly opposite portion of single wall 11, (see 10 Fig. 4); and so that, vice versa, stud sections 15a extend centrally between two adjacent stud sections 14a of the directly opposite portion of single wall 10.

The next group 14 of courses are built up on 15 the top of the first group 14 with a stud section 14a disposed centrally of two adjacent stud sections 14a immediately thereunder, incidentally, overlapping a lower stud section 15a. Likewise, the next group 15 of courses of single wall 11, are 20 built up on the top of the first group 15 with a stud section 15a disposed centrally of two adjacent stud sections 15a immediately thereunder, incidentally overlapping a lower stud section 14a. In this manner the respective single walls 10 and 25 11 may be built up to any desired height in providing a wall construction pursuant to the present invention.

For enhancing the insulating characteristics of the wall and providing a minimum of contact 30 area between the two component single walls, the stud sections overlap only partially. There will thus be provided a space between the free end of every stud section and the inner face of the opposing single wall.

35 The L-shaped bricks 13 are superimposed upon one another, at the locations of formation of the stud sections, according to a scheme providing inter-tying of such bricks with the bricks 12 of the same single wall. As clearly illustrated in 40 Fig. 6, the L-shaped bricks 13a are disposed one upon the other for each group of courses, with their vertex sections 13a coextensively superimposed and vertically aligned, and with their body legs 13b extending alternately in opposite directions from course to course. The body leg 13b plus the vertex section 13a of one L-shaped brick 45 will thus cover and reinforce the joint between a brick 12 and an L-shaped brick 13 immediately therebelow and a similar joint immediately thereabove.

50 Fig. 2, representing a plan view of a complete course of the wall construction, may be compared with Fig. 3, representing a plan view of the complete course immediately below that of Fig. 2, 55 as an illustration of the scheme of brick placement within any single group 14 or 15 of consecutive courses.

Fig. 3, representing a plan view of a complete bottom course of related consecutive course 60 groups 14 and 15, may be compared with Fig. 4, representing a plan view of the complete top course of the related consecutive course groups,

14 and 15 on which the stated bottom course rests, as an illustration of the placement of the related consecutive course groups 14 and 15, with respect to one another in attaining overlap of stud sections.

5 Whereas this invention has been illustrated and described with respect to one preferred embodiment thereof it should be clearly understood that changes may be made without departing from the spirit and scope of the invention as set forth in the following claims.

I claim:

1. A hollow brick wall comprising component single walls mutually spaced apart, and composite studs disposed therebetween at intervals 15 along the horizontal extent of the wall, each of said composite studs being integral with one and the other of the component single walls, alternately, from bottom to top, the said alternations in the composite studs being provided by individual groups of bricks, all of the bricks in any one group being consecutively aligned, being integral with only one of the component walls, having portions which form part of the main body of that component wall, and being spaced 20 apart from the other component wall to provide insulation space.

2. In wall construction, a hollow double wall comprising component single walls formed of groups of brick courses, said groups of one of the 30 component walls tying in with said groups of the other of the component walls to form composite studs integral alternately with the respective component walls along the vertical extension of the wall construction, said groups of brick courses 35 comprising special mutually similar L-shaped bricks spaced apart horizontally in each course, the L-shaped bricks of an individual course being placed with the projecting leg member of each brick extending into the hollow between 40 the two component walls, and the said L-shaped bricks of a higher individual course in any one group of courses being superimposed on the L-shaped bricks of the next lower individual course 45 of that group of courses so that their body legs 50 extend, respectively, opposite to the extensions, respectively, of the body legs of the L-shaped bricks on which they rest; the said groups of courses being superimposed so that the grouped projecting leg members of the L-shaped bricks 55 of one group of courses of one component wall overlap the grouped projecting leg members of the L-shaped bricks of the next lower group of courses of the opposite component wall, thereby providing the said composite studs for the wall 60 construction, the length of said overlap being considerably less than the length of said projecting legs so that there is insulating space left between the projecting legs and that single wall which lies opposite the terminal ends of said projecting legs.

HERBERT ALFRED FABER.
